UNITED STATES PATENT OFFICE.

SAMUEL P. ALPAUGH, OF MARTINS FERRY, OHIO, ASSIGNOR TO WHEELING SANITARY MANUFACTURING COMPANY, OF WHEELING, WEST VIRGINIA.

DESIGN FOR A BOWL FOR WATER-CLOSETS.

44,911.

Specification for Design.

Patented Nov. 25, 1913.

Application filed August 4, 1913. Serial No. 782,959. Term of patent 7 years.

To all whom it may concern:

Be it known that I, SAMUEL P. ALPAUGH, a citizen of the United States, residing at Martins Ferry, in the county of Belmont and State of Ohio, have invented a new, original, and ornamental Design for a Bowl for Water-Closets, of which the following is a specification, reference being had to the accompanying drawing, forming part thereof.

Figure 1 is a side elevation; and Fig. 2 a rear elevation, showing my new design.

I claim:

The ornamental design for a bowl for water closets, as shown.

SAM. P. ALPAUGH.

Witnesses:

EDWARD J. LALLY,
R. B. JAQUAY.
